UNITED STATES PATENT OFFICE.

JOHN FAULL, OF BATTLE CREEK, MICHIGAN, ASSIGNOR TO JOHNSON AUTOMATIC SEALER CO., LTD., OF BATTLE CREEK, MICHIGAN, A PARTNERSHIP ASSOCIATION LIMITED OF MICHIGAN.

WRAPPING MACHINE.

Application filed December 2, 1922. Serial No. 604,598.

To all whom it may concern:

Be it known that I, JOHN FAULL, citizen of the United States, and resident of Battle Creek, Michigan, have invented new and useful Improvements in Wrapping Machines, which invention is fully set forth in the following specification.

The present invention is an improvement in wrapping machines, and particularly machines in which cartons or other articles, like bread, are wrapped in waxed paper or other wrappers.

Heretofore the cartons have been fed past the folding mechanism by followers on the main conveyor chain; and it frequently happened that, particularly with light cartons, the same would become slightly displaced whereupon the folding mechanism would not act effectively and the carton would not be securely sealed in the wrapper. This was particularly the case when wrapping small cartons, as it was found that the tucker of the folding mechanism would engage the wrapper with sufficient force to displace the carton so that the folder member would not properly engage the wrapper, with the result that the rear flap would frequently not be folded against the package at all and frequently the flap would be inaccurately folded, dependent upon the degree of displacement of the package.

The object of the present invention is to provide a feeding mechanism positively controlling the carton from the time it engages the wrapper until the latter has been folded and sealed about the carton; which secures a uniform and excellent sealing of the carton in the waxed paper or other wrapper; which is self adjustable to engage and prevent damage to cartons varying in size or shape; which eliminates all danger of displacing the carton with its attendant defective sealing; and all without any sacrifice of the speed of output and by the provision of a simple and efficient mechanism.

By the present invention the carton, with the wrapper thereon, is fixedly held by the feeding mechanism as it passes the folding devices, with the result that action of the folding mechanism on the wrapper cannot displace or change the position of the carton with respect to the feeding mechanism. A uniform and efficient wrapping is thus effected at high speed.

The invention will be better understood by reference to the accompanying drawings illustrating one expression of the inventive idea, and wherein—

Fig. 1 is a longitudinal elevation, partly in section, showing one end of the carton conveyor and associated mechanism;

Fig. 2 is a detail perspective showing one of the followers provided with the clamp of the present invention;

Fig. 3 is a transverse elevation, partly in section, showing the carton infeed; and

Fig. 4 is a detail perspective showing the elements of the clamp, separated for the purpose of clear illustration.

Referring to the drawings, wherein like reference numerals indicate like parts, 5 indicates any suitable table or support along which the carton or like article is progressed past a suitable wrapper folding mechanism or other instrumentality for operating on the moving carton or article. The folding mechanism herein illustrated comprises, on each side of the table or support, an upper tucker finger 6 and a lower tucker finger 7, an upper folder finger 8 and a lower folder finger 9. Such folder mechanism is preferably of the well-known type used in the "Johnson wax-wrapper machine" and need not be specifically described. It is sufficient to note that the upper folding mechanism rotates in a counterclockwise direction around the shaft 10 and that the lower folding mechanism rotates in a clockwise direction around the shaft 11. The folding mechanisms are driven through shafts 12 and 13 and bevel gearing 14 and 15 from any suitable source of power.

A conveyor 16, preferably of the chain type, continuously progresses the cartons past the folding mechanism. This conveyor passes over suitably supported sprockets 17 one of which is mounted on shaft 18 (Fig. 3) driven through suitable means, as shaft 19 and bevel gears 20 and 21. This conveyor has mounted thereon a plurality of suitably spaced followers, each preferably consisting of a base portion 22, a standard 23 and a follower plate 24, these parts being suitably secured together and to the chain conveyor.

Each follower standard is provided with a clamp 25 pivotally mounted on a pin 26 extending through suitable apertures in

ears 27 formed on the front face of a slide 28 having brackets 29 which embrace the follower standard. The clamp 25 is independently adjustable to engage cartons 5 varying in size or shape, adjustment of the clamp being automatically effected by the carton and suitable means here shown in the form of a spring 30 carried by the pin 26, the ends of said spring bearing against the 10 slide and the clamp. The edge of said clamp is preferably curved to prevent the same from damaging the carton as the clamp moves into engagement therewith.

The slide and clamp are elevated and depressed by any suitable means to move the same into and out of engagement with the partially wrapped carton. As here shown, a spring 31, one end of which is anchored to the follower and the other end to extensions 20 31' formed on the slide, moves the slide and clamp away from the carton engaging position, and a pair of cam tracks 32 and 33, suitably mounted on the frame of the machine, move the slide and clamp into engagement with the top and front faces respectively of the carton. A pair of rollers 34 and 35 carried by pivot pin 26 engage the cam rails 32 and 33 respectively. If desired, a single roller and a single cam track may 30 be employed. The cam tracks are inclined, Fig. 1, at 38 to force the clamp and slide downwardly, and at 39 to permit the spring 31 to elevate the slide and clamp. Preferably, a cam 40 is associated with the incline 35 39 so that the elevating of the clamp and slide by reason of the engagement of the roller 34 with said cam 40 is rendered more positive.

Any suitable means for moving the cartons into position to be engaged by the followers may be employed; preferably the usual infeed belt 41 and elevator 42 are used, the wax-wrapper being fed into position over the elevator and the wrapper being folded under the carton in the usual manner and by the well-known mechanism. The follower moves the carton, with the wrapper around it, from the elevator 42 and moves the partially wrapped carton forward 50 against the finger 43 pivoted at 44 and having one end of a spring 45 secured thereto, the other end of said spring being suitably anchored. The finger yields and the carton moves under it, the finger being forced to 55 the position shown in dotted lines in Fig. 1. The cam action is so timed that the slide and clamp move downwardly toward the carton as the finger moves over the top thereof, so that just before the carton passes beyond 60 control of the finger the curved edge of the clamp slides over the front edge of the carton and the clamp securely grips the front face of the same. Arms 31' of the slide preferably engage the top of the carton, 65 providing additional clamping action of the

same against the follower. The carton is thus under positive control and not subject to any displacement with respect to the wrapper by the action of the tucking and folding fingers engaging the latter, thus obviating a great objection and solving a very difficult problem in connection with high-speed wrapping machines in which the cartons are continuously fed past the wrapping mechanism.

With such a device wherein the carton is positively controlled at every stage of the operation, it is possible to materially simplify the construction of the machine by eliminating the guide rails 46 if desired. Further, the fixed finger 47 and the pivoted finger 43, which receive the carton from the elevator, may also be removed if desired. This, however, necessitates a positioning of the cam incline 38 slightly more to the left 75 as seen in Fig. 1.

The operation of the device is as follows:

The cartons are carried by the infeed belt 41 from any suitable source of supply to the elevator 42 which raises them into the position shown at the left of Fig. 1 between the fixed and yielding fingers, the carton at the same time being enveloped by the wrapper in the usual manner. At this moment the follower moves the partially wrapped carton against the yielding finger 43, the cam inclines operating on the rollers 34 and 35 to move the slide and clamp downwardly toward the carton. The clamping action is completed just before the carton passes beyond control of the yielding finger 43 and the carton, with the wrapper, is then fixedly held as it is progressed past the folding mechanism and the hot plates (not shown). Thereafter, the spring 31 and cam 40 disengage the clamp from the carton, which latter passes on to the delivery belt.

When it is desired to feed cartons varying in size or shape past the folding mechanism, the clamp automatically adjusts itself to the size or shape of the carton, thereby preventing application of excessive pressure on the carton with the attendant damage or mutilation thereof. The clamp is therefore independently movable with respect to the 110 slide and follower and, when the clamp is moved into engagement with a carton irregular in size or shape, automatic adjustment of the clamp is effected by means of the carton and the yielding action of the 115 spring 30, the latter permitting the clamp to move in accordance with the size or shape of the carton while at the same time exerting sufficient pressure to hold the carton with the wrapper securely against the follower.

As a further means for adapting the mechanism above described to accommodate cartons of various sizes, the cam tracks 32 and 33 are attached to the frame of the ma- 130

chine so that the same may be adjusted vertically, the adjustment of the cam tracks being effected by means of bolts 46 which extend through elongated slots 47 in the 5 upper ends of brackets 48 preferably formed integral with the cam tracks. It will thus appear that the cam tracks may be adjusted to any desired height, in accordance with the size of the cartons and that 10 such adjustment will determine the extent of vertical movement of the slide 28 and clamp 25 to insure proper engagement of the latter with the carton.

Indeed, the invention, while solving an 15 important and difficult problem in wrapping machines, is not, in its broadest aspect, limited to wrapping machines but is equally applicable to any machine in which it is desired to securely hold an object while at the 20 same time feeding it past an instrumentality for operating thereon.

While one expression of the inventive idea has been heretofore described and illustrated in detail, it is to be understood 25 that the invention is not limited thereto, and that the inventive idea may be embodied in various mechanical expressions within the limits of the appended claims.

What is claimed is:—

30 1. In a machine of the character described, the combination of folding mechanism, means for feeding cartons past said folding mechanism including a follower engaging one face of the carton, a slide movable longitudinally on the follower, a clamp pivoted on said slide and automatically engaging another face of the carton before the operation of the folding mechanism, and means for automatically disengaging said clamp 40 after the operation of the folding mechanism.

2. In a machine of the character described, the combination of folding mechanism, means for feeding cartons past said folding mechanism including a follower engaging one face of the carton, a slide movable longitudinally with respect to the follower, a clamp pivoted to said slide, means for automatically engaging said clamp with 50 another face of the carton before the operation of the folding mechanism, and means for automatically disengaging said clamp after the operation of the folding mechanism.

55 3. In a machine of the character described, the combination of folding mechanism, means for feeding cartons past said folding mechanism including a follower engaging one face of the carton, a clamp slidably 60 and pivotally mounted on said follower, means automatically shifting the pivotal point of said clamp and causing the same to engage another face of the carton before the operation of the folding mechanism, and means for automatically disengaging

said clamp after the operation of the folding mechanism.

4. In a machine of the character described, the combination of folding mechanism, means for feeding cartons past said folding mechanism including a follower engaging one face of the carton, a longitudinally movable slide, a clamp pivoted to said slide, means for automatically moving said slide and clamp whereby the latter is caused to 75 engage another face of said carton prior to operation thereon by the folding mechanism, and means for automatically disengaging said clamp from the carton after operation thereon by the folding mechanism. 80

5. In a machine of the character described, the combination of folding mechanism, means for feeding cartons past said folding mechanism including a follower engaging one face of the carton, a slide, means automatically moving said slide toward the carton prior to operation thereon by the folding mechanism, means carried by the slide yieldingly engaging another face of the 90 carton during operation thereon, by the folding mechanism, and means automatically moving said slide away from the carton after operation of the folding mechanism. 95

6. In a machine of the character described, the combination of a conveyor, a follower thereon to engage one face of the carton, folding mechanism past which the cartons are fed by said conveyor, a slide carried by the follower and provided with a yielding clamp, means automatically moving said slide toward the outer end of the follower to cause engagement of the clamp with another face of the carton prior to operation of the folding mechanism, and means automatically moving said slide toward the inner end of the follower to disengage said clamp from the carton after operation of the folding mechanism thereon. 100

7. In a machine of the character described, the combination of a conveyor, a follower thereon to engage the rear face of the carton to be wrapped, a member carried by the follower and movable longitudinally thereon, a clamp pivoted on said member, means automatically moving said member and clamp into engagement with the top and front faces of the carton prior to operation of the folding mechanism, and means automatically disengaging said member and clamp from the carton after operation of the folding mechanism. 115

8. In a machine of the character described, the combination of folding mechanism, means for feeding cartons past said folding mechanism including a follower engaging the rear face of the carton to be wrapped, and automatically operable means engaging the top and front faces of the carton to hold 120

the same securely against the follower as the carton is fed past the folding mechanism, said means comprising a member carried by the follower and movable longitudinally thereon and a clamp pivoted to one side of said member.

9. In a machine of the character described, folding mechanism, means for feeding cartons past said mechanism including a follower 10 lower engaging one face of the carton, a member having translatory movement with respect to said follower and provided with a carton-engaging clamp automatically adjustable to the size of the carton, means 15 moving said member and clamp in one direction to cause engagement of the latter with another face of the carton prior to operation of the folding mechanism, and means moving said member and clamp in 20 the opposite direction to disengage the latter from the carton after operation of the folding mechanism.

10. In a machine of the character described, folding mechanism, means for feeding 25 cartons past said mechanism including a follower engaging one face of the carton, and automatically operable means engaging the carton before the same reaches the folding mechanism and disengaging the carton 30 after the same has passed said mechanism, said means comprising a spring-actuated clamp slidably and pivotally mounted on said follower, and means for imparting translatory movement to said clamp along 35 the follower.

11. In combination, wrapper folding mechanism, means for feeding cartons with wrappers thereon to said mechanism including a follower engaging the enveloped carton, and means preventing relative displacement 40 of the carton and wrapper comprising a member having translatory movement with respect to said follower and a clamp pivoted to said member and operating on movement 45 of the latter to engage and securely hold the enveloped carton against said follower.

12. In combination, wrapper folding mechanism, means for feeding articles with wrappers thereon past said folding mechanism 50 including a follower engaging the article

with the wrapper to be folded, and means preventing relative displacement of the article and wrapper while the latter is being folded by said mechanism comprising a slide mounted on the follower for translatory movement along the same and a clamp pivoted to the slide and operating on movement of the latter in one direction to engage and securely hold the enveloped article against said follower.

13. In combination, wrapper folding mechanism, means for feeding articles with wrappers thereon past said folding mechanism including a follower engaging the article with the wrapper, a member slidably mounted on the follower, a spring-actuated clamp pivotally mounted on said member for engaging the enveloped article before the same reaches said mechanism and disengaging said article after the same has passed 70 said mechanism, the spring of said clamp adjusting the same to prevent application of excessive pressure on the article by the clamp.

14. In combination, a conveyor, a flight 75 or follower carried thereby, a member slidably mounted on said follower, a clamp pivoted to said member, means controlling movement of said member and clamp toward and away from the conveyor, and means 80 controlling movement of said clamp toward and away from said follower.

15. In a machine of the character described, the combination of folding mechanism, means for feeding cartons past said 85 folding mechanism including a follower adapted to engage one face of the carton, a slide movable longitudinally with respect to said follower, a clamp pivoted to said slide, and means for automatically engaging said clamp with another face of the carton before the operation of the folding mechanism and for disengaging the clamp after the operation of said mechanism, said means being adjustable whereby the extent of 90 movement of said clamp may be varied to accommodate cartons of different sizes.

In testimony whereof I have signed this specification

JOHN FAULL.
